UNITED STATES PATENT OFFICE.

LEE S. CHADWICK, OF SHAKER HEIGHTS, OHIO, ASSIGNOR TO PERFECTION STOVE COMPANY, OF CLEVELAND, OHIO, A CORPORATION OF OHIO.

AUTOMATICALLY-CONTROLLED BURNER.

Application filed October 5, 1925. Serial No. 60,425.

This invention relates to automatically controlled fuel oil burning apparatus, and its primary purpose is to provide apparatus of this nature that is highly efficient, is thoroughly reliable, has a wide temperature range, and that may be easily and quickly adjusted to maintain different desired temperatures of limited range.

Apparatus quite similar to that herein disclosed are exhibited in applications Serial Nos. 726,657 and 30,999, filed jointly by Marc Resek, J. Alger Dahlstrom and myself, on July 18, 1924 and on May 18, 1925, respectively, and more particularly in an application filed by Marc Resek, on April 18, 1925, and bearing Serial No. 24,052.

The apparatus is intended for use in maintaining a given range of temperature in a compartment or an apartment where thermostatic means is located for controlling the apparatus. The temperature of the compartment or apartment is affected, on the one hand, by changes in heat generated by the apparatus, and, on the other hand, by changes in the atmospheric temperature.

Briefly the apparatus consists of a boiler, an atomizing burner operated by steam from the boiler and supplying heat to the boiler (as well as to the compartment or apartment that is to be heated, either directly or indirectly), means for controlling the proportion of heat applied to the boiler, as, for example, a damper movably supported between the burner and the boiler, and means operated by steam pressure for actuating the former means or damper. It is to a unique form of this steam pressure operated means that my present invention has particular reference.

In the present embodiment of the invention, this pressure operated means consists of a plurality of bellows arranged to be thrown into and out of communication with the boiler respectively as the atmospheric temperature rises and falls, so as to vary the steam pressure required to deflect the heat from the boiler, as by moving the damper toward boiler shielding position, in inverse ratio to the number of bellows in communication with the boiler.

Obviously, as the atmospheric temperature drops, a greater head of steam is required to operate the burner so as to feed more fuel and produce a hotter fire and thus bring the temperature of the compartment or apartment up to the required degree. To accom-

plish this the control mechanism functions to reduce the number of bellows that are in communication with the boiler and to permit a greater proportion of heat to be applied to the boiler. As the atmospheric temperature rises, a lesser head of steam is required to operate the burner and the control mechanism acts to increase the number of bellows that are in communication with the boiler and thus permit a lesser proportion of heat to be applied to the boiler.

In the accompanying drawings, Fig. 1 is a front elevation, and Fig. 2 a right hand side elevation of my improved fuel oil burning apparatus; Fig. 3 is a sectional left hand elevation, and Fig. 4 a sectional plan view of the apparatus; Fig. 5 is a transverse vertical section substantially on the line 5—5 of Fig. 3; Figs. 6 and 7 are sectional details of the auxiliary burner control valves; Fig. 8 is a front elevation of a plurality of bellows for controlling the damper; Fig. 9 is a side view, partly in section, of the valve for controlling the passage of steam to and its exhaust from the bellows that are shown in detail in Fig. 8, and of the electrical mechanism through which said valve is operated; Figs. 10 to 13 are sectional details on the respective, correspondingly numbered, lines of Fig. 9, the valve being shown in the same position in all views; Fig. 14 is a vertical section through the electrical mechanism for controlling the aforesaid valve; Fig. 15 is a section on the line 15—15 of Fig. 14; Figs. 16 and 17 are elevational views, at right angles to each other, of one of the pawl carrying plates of said electrical mechanism; Figs. 18 and 19 are, respectively, a side elevation and a plan view of one of the pawls of said mechanism; Fig. 20 is a wiring diagram of the electric control circuit involving the aforesaid mechanism, a thermostatic switch, and a switch operated intermittently by a moving part of the apparatus; and Fig. 21 is a sectional detail of one of the burners.

The apparatus comprises a box like casing 1, having a removable top 2, and within the lower portion of the casing is located a refractory walled combustion chamber 3 having an opening 4 in its roof through which the products are adapted to pass into a compartment 5. Housed within the rear portion of this compartment is a boiler 6 that is adapted to receive a part of the products of combustion, when the damper 7 is lifted, the

damper being fulcrumed at its forward edge on the corresponding side member of a frame 8 that surrounds the opening 4.

The rear wall of the casing 1 has an opening 10 which is adapted to register with an opening 11 in the front wall 12 of a furnace designated generally by the reference numeral 15. This furnace may be of any approved type, as, for example, a house heating furnace of the steam, hot water, or hot air variety. In adapting a furnace of ordinary construction for use with my fuel oil burning apparatus, the grate is preferably removed and the opening 10 of the apparatus is placed in register with the ash pit door so that, as a matter of fact, the fire box of the furnace into which the combustion chamber of the apparatus discharges is composed of the space which ordinarily comprises the fire pot and ash pit.

Projected through an opening 19 in the front wall of the casing 1 is a burner designated generally by the reference numeral 20, the same comprising a main section 21 and auxiliary sections 22. Fuel oil is supplied to the burner through a conduit 23 and its branches 24 from a reservoir 25 that is situated, in the present instance, on the right hand side of the apparatus, and the same is kept supplied with oil, to the level of an overflow pipe 26 that rises from the bottom of the reservoir, by means of an oil pump 27 which receives oil from a suitable source through a pipe 28 and delivers it through a pipe 29 to the reservoir. The overflow pipe 26 discharges into a pipe 30 that preferably leads to the source of supply with which the former pipe 28 communicates. The oil pump 27 is of the reciprocating type and is operated by a steam motor 33. This motor is preferably of the cylinder and piston variety and a plunger 34, carried by the piston (not shown) projects through the rear wall of the casing. Following the usual construction of motors of this kind, the valve mechanism involving a rod 35, is actuated by the plunger 34 through the intervention of a link 36 that is fulcrumed at one end to a stud 37 on the motor casing and is pivotally connected at its opposite end to the plunger 34 and intermediate its ends to the rod 35. A contact plate 40 is carried by the plunger 34 and is adapted, upon each reciprocation of the plunger, to make contact with a stationary plate 41 that is suitably carried by an adjacent part of the structure. The purpose of these contact plates will presently be described.

A steam dome 44 is connected through a nipple 45 with the top portion of the boiler 6, and steam is conducted from said dome, through pipes 47 and 48, and through a tube 49, to the main section 21 of the burner 20. Steam is also conducted, through a branch 50 of the pipe 47, to the steam motor 33. Supported on the right hand side of the casing 1

are the valves, illustrated in detail in Figs. 6 and 7, through which the passage of steam to the auxiliary burner sections 22 is controlled. The structure involving the valves is designated generally by the reference numeral 51 and it comprises a base 52 having an inlet port 53 and two outlet ports 54, the latter ports being controlled by valves 55 that are carried by frusto-conical members 56 that constitute one of the end walls of the bellows 57 whose opposite ends are swaged within openings of a plate 58. The edge of this plate is clamped between the peripheral portion of the base 52 and a flange 59 of a frame 60, the parts being secured together by cap screws 61. It will be seen from this construction that the space between the plate 58 and the base 52 and into which the inlet port 53 opens communicates with the interior of the bellows 57. Adjusting screws 63 are threaded through the frame 60 in substantially axial alignment with the valves 55, and springs 64 are compressed between spring seats 65 that are applied to said adjusting screws and the portions of the frusto-conical members 56 which carry the valves 55. A shell 67 encloses the frame 60 and bellows 57 and is held in place by a cap screw 68 that extends through an opening in the shell and is threaded into a boss 69 of the frame 60. Tubes 70 lead from the outlet ports 54 to the auxiliary sections 22 of the burner 20, while communication is established between the steam dome 44 of the boiler 6 and the inlet port 53 through a branch 72 of the steam pipe 48.

It is apparent from the foregoing construction that the steam pressure of the boiler is at all times communicated to the interior of the bellows 57. When the steam pressure exceeds the pressure of the springs 64, the bellows are expanded and lift the valves 55 off their seats so as to throw the auxiliary burner sections into communication with the steam supply. In order to cause one of the auxiliary burner sections to come into operation after the other, as when the steam pressure has reached a given value, one of the springs 64 is adjusted to a higher tension than the other, the left hand spring in Fig. 6 being shown as compressed somewhat more than the right hand spring.

Water is supplied to the boiler 6 through an inlet pipe 75, and its admission is controlled by suitable valve mechanism that is actuated by a float 76 housed within a float chamber 77 which constitutes an extension of the boiler, the float, through its connection with the valve mechanism, serving to maintain a substantially constant water level in the boiler.

Fulcrumed in the notched end portions of a bracket 80 that is located at the forward end of the casing 1 are the so-called knife-edge bearings 81 of a lever 82 that has its rear end connected, through a link 83, with

the corresponding end of the damper 7. A rod 84 constitutes the forward end of the lever 82 and the same projects through an opening 85 in the front wall of the casing. 5 A weight 86 is applied to the rod 84 and is adapted to be held in any position to which it is adjusted along the rod, by a set screw 87. The weight 86 is set to overbalance the damper 7 and hold it in open position. This 10 action is counteracted by the steam operated mechanism to which my invention has special reference and which I shall now proceed to describe.

Depending from the horizontal branch of 15 an inverted U-shaped bracket 90 that is located in the upper, forward portion of the casing 1, are a plurality of bellows, designated respectively, A, B, C, D and E. Interposed between the lower ends of the bellows 20 and the bottom walls of sockets that are formed in a cross member 95 of the lever 82, are thrust pins 96. Through connections which I shall presently describe, communication is established between the boiler 6 and 25 the bellows so that upon an accumulation of sufficient steam pressure within certain of the bellows, the rear portion of the lever 82 will be depressed against the action of the weight 86 thereby to lower the damper 7 to closed 30 position.

Suitably supported adjacent the right hand side of the apparatus is a valve which is designated generally by the reference numeral 98, the valve casing being designated 99 and the 35 valve body 100 (see Figs. 9 to 13). The valve body is secured, as by pins 101, to a shaft 102 that is supported by and between the end walls of the casing, the upper one of said end walls being removable and held to the casing by screws 103. This end wall has a stuffing 40 gland 104 to prevent leakage where the shaft extends into the valve casing. Where the shaft protrudes above the casing it has secured to it a worm wheel 106 which is adapted 45 to be driven by a worm 107 on a shaft 108. The shaft 108 is rotatably supported within the front wall of a casing 109. Secured to the inner end of the shaft 108, within said casing, is a spur gear 110, the teeth of which 50 are adapted to be engaged by the noses 111 of pawls 112 that are pivoted at 113 to pawl carrying plates 114. These plates are normally maintained in the position shown in Fig. 14 by the engagement of screws 115, that 55 are threaded for adjustment through lugs 116 of the pawl carrying plates, with the side walls of the casing 109. Pivotally connected at 117 to portions of the pawls 112, that 60 are offset with their pivots 113, are links 118 which have their upper ends pivoted to the lower ends of the movable core sections 120 of solenoids 121 and 122, housed within the enlarged upper end of the casing 109 and 65 covered by a plate 122.

65 Returning now to the valve 98, steam is ad-

mitted to the upper end of the casing 99 thereof through a pipe 125 which connects adjacent the steam dome 44 to the previously mentioned pipe 47. It will be observed from Fig. 9 that the pipe 125 enters the valve casing 99 above the valve body 100, and at a point substantially diametrically opposite the steam inlet pipe, a pipe *a* leads to the bellows A. Consequently, the bellows A is always in communication with the boiler. 70 Through pipes *b*, *c*, *d* and *e*, the valve has connection with the respective bellows B, C, D and E. The passage of steam through the pipes *b*, *c*, *d* and *e*, is controlled by the valve body 100. Formed along one side of the 75 valve body is a plurality of supply ports, *b'*, *c'*, *d'* and *e'*. Opposite the supply ports *e'* and *d'* are exhaust ports *d*² and *e*²; and the side wall of the valve body is cut away upwardly of the aforesaid port *d*² to provide 80 a passageway *x* through which the pipes *b* and *e* may communicate with the exhaust port *d*² when the valve body is in certain positions. Steam and condensate are exhausted from the lower end of the valve casing 99 through a pipe 128. 85

Figs. 10 to 13 inclusive represent transverse sections through the valve in the plane of the respective ports *b'*, *c'*, *d'* and *e'*. It will be observed that said ports terminate 90 at one end in a line parallel with the axis of the valve body, while at their other ends they progress spirally about the valve body. The same is true of the exhaust ports, as well as 95 of the passageway *x*, and the parts of the valve body which separate the supply and exhaust ports are of sufficient width to prevent simultaneous communication of any 100 one of the pipes *b* to *e* with a supply and exhaust port. 105

Located within the compartment or apartment that is to be heated by the apparatus is a thermostat 130 shown in connection with the diagram of Fig. 20. This thermostat is comprised of a base 131 on which is mounted a thermostatic element 132 the free end of which is adapted to swing between and engage contacts 133 and 134 that are adjustably carried by a plate 135 that is pivoted at 136 to the base. By swinging this plate the contacts 133 and 134 may be adjusted with respect to the thermostatic element 132 without disturbing their relative adjustment. The adjustment of the plate 135 is for the purpose of changing the mechanism to cause it to maintain different limited ranges of temperature, while the adjustment of the contacts 133 and 134 is to increase or decrease the range. To facilitate the setting of the plate 135 for given temperature ranges, it is provided with a pointer 137 which cooperates with a scale 138 on the base 131. 110 115 120 125

A source of electric energy is represented in Fig. 20 by a battery 140. One side of the battery is connected through a conductor 141 130

with the thermostatic element 135. The contact point 133 is connected through a conductor 142 with the winding of the solenoid 121, and a conductor 143 connects the contact 134 with the winding of the solenoid 122. The solenoids are grounded through a branch conductor 144. The opposite side of the battery 140 is connected through a conductor 145 with the previously mentioned contact plate 41, and the contact plate 40, which is intermittently engaged with the plate 41 through the action of the steam motor 33, is grounded through the motor structure and a conductor 146.

15 The construction of one of the burner sections is illustrated in Fig. 21. It comprises a frame 150 which incorporates tubular bosses 151 and 152 to which the oil and steam pipes are connected, respectively, by suitable unions 153. The frame incorporates sleeves 154 and 155 into which an oil nozzle 156 and a steam nozzle 157 are adapted to be inserted from the front of the frame. Each nozzle has a comparatively small duct which opens into a port 158 that is adapted to register with the corresponding tubular boss 152. Adapted to be drawn toward the frame 150 by a bolt 160 is a head 161 which bears at its opposite ends on the forward ends of the nozzles 156 and 157. 25 The bolt 160 extends through the frame and at its inner end receives a clamping nut 162. Forwardly of the frame, a second clamping nut 163 is carried by the bolt.

30 Arranged transversely of the lower portion of the casing 1 below the passageway 4 in the roof of the combustion chamber is a pre-heating burner 165. This preheating burner is in the nature of a pan having a plurality of flues 166 rising from a horizontal wall 167 below which there is an air passageway 168 that supplies air through the ducts of the flues 166 to support combustion. A quantity of suitable oil may be introduced into the burner pan through a filling spout 169 that is 35 normally closed by a cover 170, said cover also serving to close an opening 171 through which the preheating burner may be lighted.

Assuming that water is present in the boiler to the level permitted by the valve mechanism 50 controlled by the float 76, and that a supply of oil is in the reservoir 25, to set the apparatus in operation, the preheating burner is filled and lighted and the flame therefrom rises through the passageway 4 and is deflected 55 rearwardly by the damper 7 about the boiler 6, the products passing on through the opening 11 into the fire pot of the furnace, it being understood that in the absence of a given steam pressure in the boiler the damper is 60 held in elevated position by the weight 86. As soon as steam is created in the boiler it passes through the pipes 47 and 48 and through the tube 49 to the middle section 21 of the burner 20 and starts said section of the burner in operation. This main burner then supplies heat

to the boiler, and it continues to do so until sufficient steam pressure is created to depress the damper through the action of such of the bellows A to E as are in communication with the boiler. It will be recalled that the steam pressure from the boiler is communicated to the bellows through the pipe 125, valve 98, and tube a to the bellows A, and through any of the other tubes to their respective bellows accordingly as the valve body 100 is adjusted 70 within the casing 99 by the control mechanism involving the thermostat 130 and the solenoids 121 and 122. It will be assumed, for the purpose of description, that the bellows B and C, as well as bellows A, are in communication with the boiler. As soon as sufficient steam pressure is created in the boiler to act 75 through these three bellows to depress the damper against the action of the weight 86, the damper will be moved to closed position 80 and shield the boiler from the products of combustion, all of the products then issuing through the rear end of the combustion chamber 3 into the fire box of the furnace. Upon a consequential drop in the steam pressure, the damper will again rise to permit a part of the products to have access to the boiler, and under an unchanging temperature condition, the damper will finally assume and maintain 85 a medial position.

Let it now be supposed that the atmospheric temperature has dropped to such an extent that the temperature of the compartment or apartment in which the thermostat 130 is 90 situated is lowered enough to cause the thermostatic element 132 to swing to the right into engagement with contact 133 whereupon a circuit is established, each time the steam motor 33 operates to bring the contact plates 40 and 41 into engagement with each other, 95 from the battery 140, through conductor 141, thermostatic element 132, contact 133, conductor 142, solenoid 121, conductor 144, and, through the ground, the motor casing 33, contact members 40 and 41, and conductor 145, 100 back to the battery. This will result in the solenoid 121 being energized intermittently, 105 and as its movable core section is retracted, it will, through the link 118, first swing the corresponding pawl 112 to project its nose 111 110 into engagement with one of the teeth of the spur gear 110, and further movement of the core section will cause the pawl carrying plate 114 to swing about the axis of the shaft 108 and rotate the gear and consequently the shaft 115 through the medium of the pawl, each impulse 120 of current passing through the solenoid causing the shaft to be rotated a limited distance. The rotation of the shaft 108, and consequently the worm 107 that is secured to the shaft 125 forwardly of the casing 109, causes the valve body 100 to be rotated through the worm gear 106 and shaft 102. The direction of rotation of the valve body is such as will cause first the bellows C and then the bellows B 130

(provided the temperature condition on which this action is predicated exists for a sufficient length of time) to be cut off from the steam supply and exhausted through the 5 passageway α and port d^2 to the exhaust pipe 128. This reduces the number of bellows, acting through the lever 82 to depress the damper 7, to the one designated A, and consequently a much higher head of steam will 10 be required to close the damper than was the case when the three bellows were in communication with the boiler. This increased steam pressure naturally creates a hotter fire because the volume of steam being increased causes 15 a great quantity of oil to be injected with the steam into the combustion chamber. When the steam pressure reaches certain predetermined values, the valves 55 are opened through the expansion of their controlling 20 bellows 57 and steam is admitted to the auxiliary burner sections 22, thereby to further increase the fire.

While I have described the extreme case in which all bellows (excepting bellows A that 25 is always in communication with the boiler) are cut off from the steam supply and both auxiliary burners are thrown into operation, it is obvious that as soon as the temperature of the compartment or apartment rises sufficient 30 ly to cause the thermostatic element 132 to withdraw from the contact 133, the operation of the control mechanism will cease and the apparatus will remain in its newly adjusted position until a further temperature change 35 occurs that will cause the thermostatic element to swing into engagement with one or the other of the contacts 133 or 134. When the temperature rises enough to cause the thermostatic element to swing into engagement 40 with contact 134, a circuit is established through the branch of the circuit including the solenoid 122, whereupon said solenoid will be energized intermittently and, through the mechanism above described, rotate the valve 45 body in the opposite direction and throw into communication, through the ports b' , c' etc., the corresponding bellows; and as the number of bellows that are thrown into communication with the boiler increases, a lower steam 50 pressure will prevail in the boiler because of the fact that with the increased capacity of the bellows the damper 7 will be moved toward closed position under the lesser head of steam. This results in a reduction in the size 55 of the flame, the auxiliary burners becoming inactive as soon as the steam pressure recedes beyond the aforesaid predetermined values.

Having thus described my invention, what I claim is:—

60 1. In combination, an atomizing burner, a boiler situated to receive heat from the burner and from which boiler the burner receives its steam supply, means for supplying oil to the burner, means controlling the proportion of 65 heat applied to the boiler, steam operated

means communicating with the boiler for actuating the controlling means, and temperature controlled means functioning independently of the steam pressure in the boiler for varying the quantity of steam delivered to 70 said steam operated means.

2. In combination, an atomizing burner, a boiler situated to receive heat from the burner and from which boiler the burner receives its steam supply, means for supplying oil to the burner, means for controlling the proportion of heat applied to the boiler, a plurality of steam operated devices adapted 75 to have communication with the boiler for actuating the controlling means, and temperature controlled means functioning independently of the steam pressure in the boiler for throwing certain of said devices into and out of communication with the boiler.

3. In oil burning apparatus for heating a 80 compartment, in combination, an atomizing burner, a boiler situated to receive heat from the burner and from which boiler the burner receives its steam supply, means for supplying oil to the burner, means controlling the proportion of heat applied to the boiler, steam operated means communicating with the boiler for actuating the controlling means, means functioning independently of the steam pressure in the boiler for varying the 85 quantity of steam delivered to said steam operated means, and thermostatic mechanism subjected to the temperature in the compartment for controlling said quantity varying means.

4. In oil burning apparatus for heating a 90 compartment, in combination, an atomizing burner, a boiler situated to receive heat from the burner and from which boiler the burner receives its steam supply, means for supplying oil to the burner, a member arranged to intercept the passage of heat from the burner to the boiler and movable between a position wherein it does, and a position wherein it does not, shield the boiler from the heat 95 of the burner, said member tending to move toward one of said positions, a plurality of steam operated devices for moving said member to the other position, conduits for delivering steam from the boiler to the respective 100 devices, valve mechanism functioning independently of the steam pressure in the boiler for controlling the passage of steam to the devices, and thermostatic mechanism subjected to the temperature in the compartment for controlling said valve mechanism.

5. In oil burning apparatus for heating a 105 compartment, in combination, an atomizing burner, a boiler situated to receive heat from the burner and from which boiler the burner receives its steam supply, means for supplying oil to the burner, a member arranged to intercept the passage of heat from the burner to the boiler and movable between a position wherein it does, and a position wherein it does 110

not, shield the boiler from the heat of the burner, said member tending to move toward one of said positions, a plurality of steam operated devices for moving said member to the other position, conduits for delivering steam from the boiler to the respective devices, valve mechanism for controlling the passage of steam to the devices, and thermostatic mechanism subjected to the temperature in the compartment for actuating the valve mechanism.

6. In combination, an atomizing burner, a boiler situated to receive heat from the burner and from which boiler the burner receives its steam supply, means for supplying oil to the burner, means controlling the proportion of heat applied to the boiler, steam operated means communicating with the boiler for actuating the controlling means, a valve for varying the quantity of steam delivered to said steam operated means, a pair of solenoids having operative connection with said valve whereby the energization of one of said solenoids causes the valve to be moved in one direction while the energization of the other solenoid causes the valve to be moved in the opposite direction, an electric circuit including a source of energy and two branches, each branch involving the winding of one of the aforesaid solenoids, a thermostatic switch in said circuit by means of which one or the other of the branches is electrically connected with the source of energy, a second switch in the circuit, and means for intermittently closing said second switch.

7. In combination, an atomizing burner, a boiler situated to receive heat from the burner and from which boiler the burner receives its steam supply, means for supplying oil to the burner, a member arranged to intercept the passage of heat from the burner to the boiler, said member being movable from a position wherein it shields the boiler from the heat of the burner to a second position wherein it is ineffective, the member tending to move toward one of said positions, a plurality of steam operated devices for moving the member toward the other position, conduits through which steam is delivered from the boiler to said devices, and valve mechanism controlling the passage of steam through said conduits, the valve mechanism serving, when moved in one direction, to throw said devices successively into communication with the boiler and, when moved in the opposite direction, to similarly cut off the steam supply to said devices and exhaust them.

8. In combination, an atomizing burner, a boiler situated to receive heat from the burner and from which boiler the burner receives its steam supply, means for supplying oil to the burner, a member arranged to intercept the passage of heat from the burner to the boiler, said member being movable between a posi-

tion wherein it shields the boiler from the heat of the burner and a second position wherein it is ineffective, the member tending to move toward one of said positions, a plurality of steam operated devices for moving the member toward the other position, conduits through which steam is delivered from the boiler to said devices, valve mechanism controlling the passage of steam through said conduits, the valve mechanism serving, when moved in one direction, to throw said devices successively into communication with the boiler and when moved in the opposite direction to similarly cut off the steam supply to said devices and exhaust them, mechanism for actuating said valve involving two solenoids, one of which when energized moves the valve in one direction, the other when energized serving to move the valve in the opposite direction, an electric circuit including a source of energy and two branches, each branch involving the winding of one of said solenoids, a thermostatic switch for electrically connecting one or the other of said branches with the source of energy, a second switch in said circuit, and means for intermittently closing said second switch.

9. In combination, a plurality of atomizing burners, a boiler situated to receive heat from said burners, conduits leading from the boiler to said burners, valves in certain of said conduits, steam operated devices connected to said valves and serving to open them when the steam pressure within the boiler attains predetermined values, means for supplying oil to the burners, means controlling the proportion of heat applied to the boiler, steam operated means communicating with the boiler for actuating the controlling means, and temperature controlled means functioning independently of the steam pressure in the boiler for varying the quantity of steam delivered to the last mentioned steam operated means.

10. In oil burning apparatus for heating a compartment, in combination, a plurality of atomizing burners, a boiler situated to receive heat from said burners, conduits leading from the boiler to said burners, valves in certain of said conduits, steam operated devices connected to said valves and serving to open them when the steam pressure within the boiler attains predetermined values, means for supplying oil to the burners, means controlling the proportion of heat applied to the boiler, steam operated means communicating with the boiler for actuating the controlling means, and thermostatic means subjected to the temperature in the compartment for varying the quantity of steam delivered to the last mentioned steam operated means.

11. In combination, a plurality of atomizing burners, a boiler situated to receive heat from said burners, conduits leading from the boiler to said burners, valves in certain of said

conduits, steam operated devices connected to said valves and serving to open them when the steam pressure within the boiler attains predetermined values, means for supplying oil to the burners, means controlling the proportion of heat applied to the boiler, a plurality of steam operated devices adapted to have communication with the boiler for actuating the controlling means, and temperature controlled means functioning independently of the steam pressure in the boiler for throwing certain of said devices into and out of communication with the boiler.

12. In oil burning apparatus for heating a compartment, the combination of an atomizing burner, a boiler situated to receive heat

from the burner and from which boiler the burner receives its steam supply, means for supplying oil to the burner, means for controlling the proportion of heat applied to the boiler, a plurality of steam operated devices adapted to have communication with the boiler for actuating the controlling means, means for throwing certain of said devices into and out of communication with the boiler, and thermostatic mechanism subjected to the temperature in the compartment for controlling the last mentioned means.

In testimony whereof, I hereunto affix my signature.

LEE S. CHADWICK.
